UNITED STATES PATENT OFFICE

CHARLES H. WATERMAN, OF ATHENS, MICHIGAN.

DESIGN FOR A WIRING-CLEAT.

44,117.

Specification for Design.

Patented May 27, 1913.

Application filed March 18, 1912. Serial No. 684,628. Term of patent 3½ years.

To all whom it may concern:

Be it known that I, CHARLES H. WATERMAN, a citizen of the United States, residing at Athens, in the county of Calhoun and State of Michigan, have invented a certain new, original, and ornamental Design for Wiring-Cleats, of which the following is a specification, reference being had to the accompanying drawings.

Figure 1 is a plan view of my wiring cleat. Fig. 2 is an end view. Fig. 3 is a front view. Fig. 4 is a rear view. Fig. 5 is a bottom view.

As shown in the views, the wiring cleat is substantially rectangular with rounded end corners, and has a vertical open-ended

passage bell-shaped at the bottom, and on its top, disposed at each corner from one side thereof, it is provided with an inwardly-overhanging lug, and on the opposite side and centrally thereof it has an inwardly overhanging lug, the two former being spaced from the latter and the three being arranged with a tortuous rounded passage therebetween.

I claim—

The ornamental design for a wiring cleat as shown and described.

CHAS. H. WATERMAN.
